US00D966680S

(12) **United States Design Patent** (10) **Patent No.:** **US D966,680 S**
Dunham (45) **Date of Patent:** **** Oct. 18, 2022**

(54) **FOOTWEAR**

(71) Applicant: **Target Brands, Inc.**, Minneapolis, MN (US)

(72) Inventor: **Austyn Dunham**, Minneapolis, MN (US)

(73) Assignee: **Target Brands, Inc.**, Minneapolis, MN (US)

(**) Term: **15 Years**

(21) Appl. No.: **29/754,802**

(22) Filed: **Oct. 14, 2020**

(51) **LOC (13) Cl.** **02-04**

(52) **U.S. Cl.**

USPC **D2/970**; D2/972

(58) **Field of Classification Search**

USPC ..... D2/896, 901–909, 916, 944, 946, D2/969–974; 36/45, 50.1, 77 M, 83, 88, 36/89, 114–116, 1.5, 2 R, 109, 3 A, 112, 36/100, 7.1 R, 7.3, 102, 113

(57) **CLAIM**

The ornamental design for a footwear, as shown and described.

DESCRIPTION

FIG. 1 is a front, top and right side perspective view of an embodiment of a footwear according to the new design;

FIG. 2 is a front side elevation view thereof;

FIG. 3 is a back side elevation view thereof;

FIG. 4 is a right side elevation view thereof;

FIG. 5 is a left side elevation view thereof; and,

FIG. 6 is a top plan view thereof.

The bold broken lines in the drawings represent stitching and are part of the claimed design. The non-bold broken lines in the drawings show portions that form no part of the claimed design.

1 Claim, 6 Drawing Sheets
